[57] CLAIM

The ornamental design for a housing for magnetic contact switch component, as shown and described.

DESCRIPTION

FIG. 1 is a front elevational view of a housing for a magnetic contact switch component embodying our new design;

FIG. 2 is a fragmentary top plan view thereof, the housing being fragmentary shown for convenience of illustration;

FIG. 3 is a bottom plan view thereof.

FIG. 1

FIG. 2

FIG. 3
